(57) **CLAIM**

The ornamental design for a multi-curve mirror, as shown and described.

DESCRIPTION

FIG. 1 is a top plan view of a multi-curve mirror showing our new design;

FIG. 2 is a cross sectional view taken along line 2—2 in FIG. 1;

FIG. 3 is another cross sectional view taken along line 3—3 in FIG. 1;

FIG. 4 is a bottom plan view thereof; and,

FIG. 5 is a side elevation view thereof.

The broken lines shown in FIGS. 4 and 5 are for illustrative purposes only and form no part of the claimed design.
